No. 37,041.

Patented July 12, 1904.

UNITED STATES PATENT OFFICE.

ROBERT MARTINDALE, OF INDIANAPOLIS, INDIANA.

DESIGN FOR A RADIATOR.

SPECIFICATION forming part of Design No. 37,041, dated July 12, 1904.

Application filed March 29, 1904. Serial No. 200,800. Term of patent 14 years.

To all whom it may concern:

Be it known that I, ROBERT MARTINDALE, a citizen of the United States, residing in Indianapolis, in the county of Marion and State 5 of Indiana, have invented a new, original, and ornamental Design for a Radiator.

The drawing shows in perspective a radiator embodying the present design.

I claim—
The ornamental design for radiator illustrated in the accompanying drawing.

ROBERT MARTINDALE.
